UNITED STATES PATENT OFFICE.

PETER J. LA BELLE, OF BIRMINGHAM, ALABAMA, ASSIGNOR OF ONE-HALF TO EDWARD WALD, OF BIRMINGHAM, ALABAMA.

SASH-LOCK.

988,114.

Specification of Letters Patent. Patented Mar. 28, 1911.

Application filed April 6, 1910. Serial No. 553,722.

To all whom it may concern:

Be it known that I, PETER J. LA BELLE, a citizen of the United States of America, residing at Birmingham, in the county of 5 Jefferson and State of Alabama, have invented new and useful Improvements in Sash-Locks, of which the following is a specification.

This invention relates to a combined sash 10 lock and lift, the object being to provide a structure operable to release the sash in movement thereof to its open position.

In the drawings, forming a portion of 15 this specification and in which like numerals of reference indicate similar parts in the several views:—Figure 1 is a front elevation of my improved sash lock, and lift showing the same in its applied position on a window sash and casing, parts being shown 20 in section to clearly illustrate the invention. Fig. 2 is a vertical section therethrough. Fig. 3 is a view similar to Fig. 1 showing the movable locking members moved to their released positions.

Upon reference to Figs. 1 to 3 inclusive 25 of the drawings, it will be observed that my improved sash lock and lift consists of a casing 1 which may be of any suitable well known and desired design. As shown, the 30 said casing is provided with flanges 2 which are secured to the window sash A by fastening devices 3. The casing is provided with an opening 4 which is disposed in line with an opening 5 in a keeper-plate 6 which 35 is secured to the casing B, as illustrated. The casing is provided with companion pivot posts 7 on which are pivotally mounted locking dogs 8 each being provided with an arm 9 which extends upwardly and out- 40 wardly substantially at an obtuse angle to the pivot of the dog, a foot 10 and a nose 11. The feet are formed to provide hooked portions 12 which are operable to engage the member 13 of the keeper-plate. The arms 45 9 of the said locking dogs extend outwardly in opposite directions and through passages 14 of the head 15 of an actuating member 16 which is movable vertically in the casing. The member extends through the upper por- 50 tion of the casing and is formed to provide a finger-receiving element 17 for a purpose

to be hereinafter described. A spring 18 is coiled about the shank of the actuating member 16, and as illustrated, one end bears against the said head 15 and its opposite 55 end bears against the top of the casing so that the spring exerts its tension against the head 15 to cause the same to normally assume the position shown in Fig. 1 of the drawings. This construction is such that 60 through the just described engagement of the head 15 of the actuating member with the locking dogs, the said dogs will be normally held engaged with the keeper-plate to hold the sash against movement. The cas- 65 ing is formed to provide stops 19 for a purpose to be hereinafter explained. The members 21' are secured to the head 15. To further insure the engagement of the dogs with the keeper-plate I provide leaf springs 70 22 whose free ends bear against the nose portions 11 of the locking dogs, as shown. The stops 19 bear against the springs to insure a proper tension against the dogs. The members 21' are provided with guide lugs 75 11' which operate to engage the side walls of the casing 1 to insure an accurate sliding movement of the actuating member.

In operation of the herein described lift and lock, assuming it to be the desire of the 80 operator to move the sash to an open position pressure is applied on the actuating member to move it against the tension of the spring 18 and also against the tension of the springs 22. In this movement of the 85 actuating member the arm portions 9 of the locking dogs will be engaged by the walls of the slots 14 in the head 15 to rock such dogs and to move them out of locking engagement with the keeper-plate. The construction described is such that the actuating member is constructed not only as a means for releasing the dogs from the keeper-plate but as a grip to enable the operator to conveniently manipulate the sash. 90

I claim:

A sash lock comprising a pivoted dog mounted on the sash, a keeper located in the path of movement of the dog, the said dog having an arm which extends upwardly and outwardly substantially at an obtuse angle to said dog, and a sliding actuating mem- 100

ber having an aperture receiving the arm of the dog, said arm being slid able between the walls of the aperture and bearing there-against so that in one movement of the ac-
5 tuating member movement will be imparted to the dog to release the same from the keeper.

In testimony whereof I affix my signature in presence of two witnesses.

PETER J. LA BELLE.
